LETTERING SCRIBER

Walter Harry Schneider, Ridgefield, N. J., assignor
to Keuffel & Esser Company, Hoboken, N. J., a
corporation of New Jersey

Application March 5, 1949, Serial No. 79,797

4 Claims. (Cl. 33—23)

1

This invention relates to lettering instruments. It is useful in lettering instruments of the general type shown and described in U. S. Patent 2,011,195 to Adolf W. Keuffel. This type of lettering instruments consists of a scribe provided with a writing instrument having a tracer pin and a tail pin; and a template provided with indicia or markings which may be followed by the tracer pin and a tail pin groove parallel to the direction of lettering for receiving the tail pin. The term indicia as used herein is meant to include all types of markings which may be reproduced, such as letters, numbers, electrical symbols, welding symbols and the like.

It has become the practice in the manufacture of templates for this type of lettering instrument to make templates of at least two widths. The wider templates may be for the purpose of carrying larger indicia or several rows of indicia. The adjustable scribe is used with the narrow width template in the manner described in Patent No. 2,011,195.

The spacing between the writing instrument and tracer pin on the adjustable scribe is not great enough when the scribe is in its closed or normal position to permit the scribe to be used with the wide form of template but it is possible to use the adjustable scribe in an open or adjusted position with the wide template since the adjustment increases the spacing between the writing instrument and tracer pin.

As described in the aforementioned patent the usual template has indicia which are backwardly inclined by a predetermined amount so that the adjustable scribe will draw erect indicia in its closed or normal position. If the spacing between the writing instrument and the tracing pin on the adjustable scribe is increased from the closed or normal position, the scribe will draw forwardly slanted letters if the same template is used.

If the wider form of template is provided with indicia having the same backward slant, the adjustable scribe in open position will draw forwardly slanted letters. In order for the adjustable scribe to draw upright indicia in its open position, it was necessary to increase the backward inclination of the indicia on the templates. In using this system, it was necessary to make the wider templates with differently slanted indicia than the ordinary templates. This complicated the manufacture of the templates.

The invention is also applicable to the lettering instrument having an adjustable scribe disclosed in patent application Serial No. 6,576, filed February 6, 1948.

The principal object of the invention is to provide a tail piece extension for an adjustable scribe of a lettering instrument so that it may be used in the open position with a wide template

to draw erect indicia when the indicia on the template are inclined only the normal amount.

This and other objects of the invention and the method of their attainment will be more fully understood from the following description taken in connection with the accompanying drawing in which:

Figure I is a view in plan of the lettering instrument shown and described in Patent No. 2,011,195 with a tail piece extension arm secured to the adjustable scribe thereof.

Figure II is a view in elevation and partly in section of the tail piece extension arm shown in Figure I.

Figure III is a view in plan looking from the underneath side of the arm as shown in Figure I.

Figure IV is a view in plan of the lettering instrument shown and described in patent application Serial No. 6,576, filed February 6, 1948, with a tail piece extension arm secured to the adjustable scribe thereof.

Figure V is a view in elevation and partly in section of the tail piece extension arm shown in Figure IV.

Figure VI is a view in plan of the tail piece extension arm looking from the underneath side of the arm as shown in Figure IV.

Referring to Figure I, the adjustable scribe 11 is provided with a tail piece extension arm 60 and is arranged for use with the wide template 16. The template 16 is provided with a tail pin groove 18 and indicia grooves 15. The scribe 11 is made up of a body portion 23, a tail pin arm 22, a writing instrument arm 25 and an adjustable tracer pin arm 24. The tail piece 22 normally carries a tail pin at 17 but this has been removed to permit the extension 60 to be secured to the scribe 11. The writing instrument arm 25 is provided with means for holding a writing instrument which in this case is the pen 12. The adjustable tracer pin arm carries the tracer pin 14.

The adjustable tracer pin arm pivots around the pin 62 carried within the body 23 of the scribe 11. An arcuate slot 68 is provided in the tracer pin arm 24 which receives the pin 69 carried by the body 23 of the scribe 11. The pin 69 limits the pivotal motion of the tracer pin arm 24 and is threaded to receive the knurled nut 74 at its lower extremity. The knurled nut 74 serves to clamp the tracer pin arm in adjusted position.

In Figure I the adjustable arm 24 is shown adjusted to a predetermined open position. It is shown in dotted lines in its normal closed position. When the adjustable scribe is assembled with the tail pin in its normal position and with the adjustable scribe in its closed or normal position, the writing instrument, tracer pin and

tail pin form the vertices of a triangle 12, 14', 17'. The tail pin extension arm 60 is provided with such dimensions that the tail pin 17, writing instrument 12 and tracer pin 14 in predetermined position form the vertices of a triangle 12, 14, 17. It is necessary that the triangle 12, 14, 17 be substantially geometrically similar to the triangle 12, 14', 17', in order that the open scribe with tail pin extension will draw erect indicia 13 from the indicia 15 provided on the template 16 and having the normal backward slant as will permit the adjustable scribe in normal position without tail piece extension to draw erect indicia. The dimensions of the tail piece extension 60 that will accomplish this result will depend on the dimensions of the adjustable scribe including the position of the pivot pin 62 for the adjustable tracer pin arm and the desired predetermined spacing between the writing instrument 12 and the tracer pin 14 which will in turn depend on the width of the template 16. These dimensions may be readily ascertained for any given adjustable scribe and any given template by a person skilled in the art.

In order that the spacing between the writing instrument 12 and the tracer pin 14 may be accurately set to the predetermined value when using the tail pin extension 60, a pair of marks or holes 80 and 82 are provided on the template 16. The spacing may be readily set to the predetermined value by comparison with the marks 80 and 82.

The tail piece extension arm 60 shown in Figures II and III is provided with an opening 84 on its under side accurately made to receive the tail pin arm 22 of the scribe 11. The hole 86 provided at the top of the extension arm 60 opens into the opening 84. In order to apply the tail piece extension arm 60 to the adjustable scribe 11, the tail pin must be removed from the tail pin arm 22. The tail pin arm is then inserted in the opening 84 of the extension arm 60 so that the hole 86 lines up with the hole 17'. The tail pin extension arm may then be secured to the tail pin arm 22 by a screw 88 passing through the hole 86 and engaging threads in the hole 17' which is threaded to receive either the tail pin, i. e., the screw 35 or the screw 88.

The tail pin 17 may be secured to the tail pin extension arm 60 in the same manner as it is normally secured to the tail pin arm and as is shown and described in Patent No. 2,050,058. The pin 17 is tightly fitted in an axial hole provided in a screw 35. The screw 35 is provided with a head 34 which determines the spacing between the lower surface of the extension arm 60 and the template 16. The screw 35 engages threads in the hole 36 provided in the extension arm 60 thereby securing the tail pin 17 to the extension arm 60. A weight 38 may be provided which has a threaded hole to engage the screw 35. The weight 38 is preferably of lead and helps to prevent the tail pin from coming out of the tail pin groove 18.

Referring to Figure IV, the adjustable scribe 138 is provided with a tail pin arm 142, a tracer pin arm 148, an adjustable writing instrument arm 150 and a body portion 140. The tail pin arm normally carries a tail pin at 152, but in Fig. IV the tail pin extension arm 260 is secured thereto. The tracer pin arm 148 carries the tracer pin 154. The writing instrument arm is provided with means for carrying a writing instrument which in this embodiment is the pen 156.

The writing instrument arm 150 pivots about

the pin 145 and is provided with an arcuate slot 172. The fixed pin 170 passes through the arcuate slot 172 and limits the motion of the writing instrument arm 150. The lever 180 engages threads on the pin 170 and clamps the adjustable writing instrument arm 150 in adjusted position.

The adjustable writing instrument arm 150 is shown in an adjusted open position with the writing instrument 156 spaced at a predetermined distance from the tracer pin 154. The writing instrument arm 150 is also shown in dotted lines in its normal position. When the writing instrument arm 150 is in its normal position, the writing instrument 156, the tracer pin 154 and the normal position for the tail pin 152 form a right triangle 152, 154, 156'.

When the writing instrument arm 150 is adjusted to its predetermined open position and the tail pin extension arm 260 is secured to the tail pin arm 142, the writing instrument 156, the tracer pin 154 and the tail pin 217 form the vertices of a triangle 217, 154, 156. The triangle 217, 154, 156 should be substantially geometrically similar to the triangle 152, 154, 156' in order that the scribe in predetermined adjusted position with the tail pin extension arm attached will produce erect indicia from a template provided with indicia slanted backward in the normal manner.

In the embodiment of Figure IV the triangles 152, 154, 156' and 217, 154, 156 will be right triangles for the reasons described in patent application Serial No. 6,576 already referred to.

The template 102 may also be provided with two spaced marks or holes 280 and 282 for setting the spacing between the tracer pin 154 and the writing instrument 156 to the predetermined amount. This is the preferred method but this setting may also be accomplished by reference to an ordinary scale graduated in inches or any other convenient unit. The setting may also be made by means of the index mark 184 and the scale 182.

The construction of the tail piece extension arm 260 as shown in Figures V and VI is equivalent to the construction of the extension arm 60 in Figure I except that the dimensions are chosen to correspond to the adjustable scribe 138 instead of the adjustable scribe 11.

By adhering to the principle of similar triangles herein taught the invention can be readily applied to a wide variety of designs for adjustable scribes. Equivalent means for securing the extension arm to the tail pin arm may also be used within the spirit and scope of the invention.

Having thus described the invention, what is claimed is:

1. An extension for the tail piece of an adjustable scribe having a writing instrument, a tracer pin and a tail pin forming the vertices of a triangle, the spacing between the tracer pin and the writing instrument being adjustable to spacings greater than the normal spacing at which the scribe draws erect indicia with the tail pin in its normal position on the scribe from a template having characters inclined at a predetermined angle, said extension comprising an arm having means for carrying a tail pin and means for securing said arm to the scribe, so that when said arm is secured to the scribe and the scribe is adjusted to make the spacing between the writing instrument and the tracer pin equal to a predetermined increased spacing, said means for

carrying the tail pin is in such a position that a tail pin carried thereby together with the writing instrument and tracer pin in their adjusted positions form the vertices of a triangle which is substantially geometrically similar to the triangle formed by the writing instrument, tracer pin and tail pin when the tracer pin and writing instrument are adjusted to their normal spacing and the tail pin is in its normal position on the scribe.

2. A lettering instrument of the type described comprising an adjustable scribe having a writing instrument, a tracer pin and a tail pin forming the vertices of a triangle and which may be used with a normal width template having a tail pin groove and indicia grooves inclined at a predetermined angle, the spacing between the tracer pin and the writing instrument being adjustable to spacings greater than the normal spacing at which the scribe draws erect indicia with the tail pin in its normal position on the scribe from the normal width template; an extension arm for said scribe having means for carrying a tail pin; means for securing the extension arm to the scribe; a template wider than the normal width template having a tail pin groove and indicia grooves inclined to the same predetermined angle as in the normal width template, the width of said template being greater than the maximum width which would permit complete indicia to be drawn therefrom with the normal spacing between the tracer pin and writing instrument and a pair of spaced marks on said wider template for setting the spacing between the tracer pin and writing instrument to a predetermined adjusted position, so that when said arm is secured to the scribe and the scribe is adjusted to make the spacing between the writing instrument and the pin equal to the predetermined amount, said means for carrying the tail pin is in such a position that a tail pin carried thereby together with the writing instrument and tracer pin in adjusted position form the vertices of a triangle which is substantially geometrically similar to the triangle formed by the writing instrument, tracer pin and tail pin when the tracer pin and writing instrument are adjusted to their normal spacing and the tail pin is in its normal position on the scribe.

3. An extension for a scribe having a writing instrument arm, an adjustable tracer pin arm and a tail pin arm, which arms carry a writing instrument, a tracer pin and a tail pin forming the vertices of a triangle, the adjustment of the tracer pin arm being capable of increasing the spacing between the tracer pin and the writing instrument to spacings greater than the normal spacing at which the scribe draws erect indicia with the tail pin in its normal position on the

scriber from a template having characters inclined at a predetermined angle, said extension comprising an arm which may be secured to the scribe for extending said tail pin arm having means for carrying a tail pin so that when said arm is secured to the scribe and the scribe is adjusted to make the spacing between the writing instrument and the tracer pin equal to a predetermined increased spacing, said means for carrying the tail pin is in such a position that a tail pin carried thereby together with the writing instrument and tracer pin in adjusted position form the vertices of a triangle which is substantially geometrically similar to the triangle formed by the writing instrument, tracer pin and tail pin when the tracer pin arm is adjusted to give the normal spacing between the tracer pin and writing instrument and the tail pin is in its normal position on the scribe.

4. An extension for a scribe having an adjustable writing instrument arm, a tracer pin arm and a tail pin arm, which arms carry a writing instrument, a tracer pin and a tail pin forming the vertices of a triangle, the adjustment of the tracer pin arm being capable of increasing the spacing between the tracer pin and the writing instrument to spacings greater than the normal spacing at which the scribe draws erect indicia with the tail pin in its normal position on the scribe from a template having characters inclined at a predetermined angle, said extension comprising an arm which may be secured to the scribe for extending said tail pin arm having means for carrying a tail pin so that when said arm is secured to the scribe and the scribe is adjusted to make the spacing between the writing instrument and the tracer pin equal to a predetermined increased spacing said means for carrying the tail pin is in such a position that a tail pin carried thereby together with the tracer pin and writing instrument in adjusted position form the vertices of a triangle which is substantially geometrically similar to the triangle formed by the writing instrument, tracer pin and tail pin when the writing instrument arm is adjusted to give the normal spacing between the tracer pin and writing instrument and the tail pin is in its normal position on the scribe.
